Primary Examiner — Jasmine Mlinarcik(74) *Attorney, Agent, or Firm* — Saul Ewing LLP; Brian R. Landry(57) **CLAIM**

The ornamental design for a headwear, as shown and described.

DESCRIPTION

FIG. 1 is a perspective view of the front, and left side of a headwear showing an embodiment of the new design;
FIG. 2 is a perspective view of the front, left side and top thereof;

FIG. 3 is a left side view thereof;

FIG. 4 is a right side view thereof;

FIG. 5 is a top view thereof;

FIG. 6 is a bottom view thereof;

FIG. 7 is a front view thereof; and,

FIG. 8 is a rear view thereof.

The broken lines depict features of the headwear that form no part of the claimed design.
